HAIR STYLING TOOL

Hector S. Cournoyer, 7545 E. Treasure Drive, Treasure Island, Miami Beach, Fla. 33139

Continuation of design applications Ser. No. 85,312 and Ser. No. 85,313, May 17, 1965. This application Feb. 28, 1966, Ser. No. 1,427

Term of patent 14 years

(Cl. D86—8)

FIG. 1 is a perspective view of a hair styling tool, showing my new design;

FIG. 2 is an elevational view thereof;

FIG. 3 is a vertical sectional view taken on the plane of line 3—3 of FIG. 2;

FIG. 4 is a top plan view of FIG. 2;

FIG. 5 is a sectional view taken on the plane of line 5—5 of FIG. 2;

FIG. 6 is an elevational view of the side opposite that shown in FIG. 2;

FIG. 7 is a perspective view of another embodiment of a hair styling tool, showing my new design, with the prongs angled laterally from the handle;

FIG. 8 is an elevational view of FIG. 7;

FIG. 9 is a vertical sectional view taken on the plane of line 9—9 of FIG. 8;

FIG. 10 is a top plan view of FIG. 8;

FIG. 11 is a sectional view taken on the plane of line 11—11 of FIG. 8; and

FIG. 12 is an elevational view of the side opposite that shown in FIG. 8.

Portions of FIGS. 1, 2, 4—6, 7, 8, and 10—12 are broken away to show the indefinite width of the tool.

This application is a continuation of copending United States applications Serial No. 85,312 and Serial No. 85,313 each filed on May 17, 1965.

I claim:

The ornamental design for a hair styling tool, as shown and described.
